Primary Examiner — Llorellys Martinez(74) *Attorney, Agent, or Firm* — Eric Kelly(57) **CLAIM**

The ornamental design for a bracelet, as shown and described.

DESCRIPTION

FIG. 1 is a top perspective view of a bracelet showing my new design;

FIG. 2 is a right-side view thereof;

FIG. 3 is a left-side view thereof;

FIG. 4 is a front view thereof;

FIG. 5 is a rear view thereof;

FIG. 6 is a top view thereof;

FIG. 7 is a bottom view thereof; and,

FIG. 8 is a bottom perspective view thereof.

The broken lines in the drawings illustrate portions of the bracelet that form no part of the claimed design.

The bracelet is shown with a symbolic break in its length. The appearance of any portion of the bracelet between the break lines forms no part of the claimed design.
